UNITED STATES PATENT OFFICE

JAMES R. FOUCH, OF LOS ANGELES, CALIFORNIA

MICROPHONE RADIO CUT-OUT SWITCH

Application filed January 12, 1931. Serial No. 508,190.

This invention relates to an improved microphone radio cut-out switch, and has for one of its principal objects the provision of a microphone and an attached cut-out switch whereby local broadcasting may be accomplished.

One of the important objects of this invention is to provide a microphone and related apparatus which will enable the owner 10 of a radio set to use the same for amplification purposes of his own, and also whereby a radio set with extension loud speakers can be used in making emergency announcements or any sort of local broadcasting accomplished as, for example, in business houses 15 or apartment buildings where a plurality of radio sets or loudspeakers are installed.

Other and further important objects of the invention will be apparent from the disclosures in the accompanying drawings and 20 following specification.

The invention, in a preferred form, is illustrated in the drawings and hereinafter more fully described.

25 In the drawings:

Figure 1 is an elevation showing the improved microphone radio cut-out switch of this invention as applied to an ordinary radio set.

30 Figure 2 is an interior view of the microphone and its related switch, showing the same in one position.

Figure 3 illustrates another positioning of the switch for use with certain forms of 35 radio sets.

Figure 4 is a rear interior view of the microphone proper, illustrating particularly the wiring connections.

40 As shown in the drawings:

The reference numeral 10 indicates generally an ordinary radio set of any conventional type, and the reference numeral 12 indicates generally the power tube or the like which actuates the loud-speaker of the set.

45 The device of this invention includes particularly a microphone casing 14 having the usual diaphragm 16 therein and mounted on a stand or base 18.

A pair of wires 20 and 22 lead from the 50 microphone, the wire 20 being in electrical

contact with the frame or casing of the microphone, and the wire 22 being insulated from the frame and terminating at a binding post 24 which comprises a screw or the like supporting in position a leaf spring 26 which 55 forms a switch element.

The end of the leaf spring 26 is shaped as best shown in Figures 2 and 3, and a push-button 28 of some insulating material is mounted in a suitable opening in the top of 60 the microphone casing 14, passing therethrough and contacting with the end of the switch.

A set screw 30 is mounted in the frame adjacent the push-button 28, and as shown in 65 Figure 2, this set screw when not screwed entirely down will not contact the switch element 26, thereby leaving an open circuit, which, however, is closed when the pushbutton 28 is depressed, forcing the inturned 70 end of the spring into contact with the adjacent portion of the mounting for the diaphragm 16. When the screw 30 is set into its lowermost position, it contacts with the spring 26 as shown in Figure 3, and a downward 75 motion of the push-button 28 breaks any circuit which has been established.

In operation, the free ends of the wires 20 and 22 are plugged in or otherwise attached, one to the power tube 12 which actuates the 80 loud-speaker, and the other to the radio set chassis as shown at 34, this constituting a ground, or an actual ground connection may also be made.

By manipulating the button, the microphone 85 14 may be cut in onto the loud-speaker of the radio set 10, and at the same time the radio reception is cut off. This accordingly permits the operator of the microphone to accomplish local broadcasting through his 90 own or connected sets, this being obviously quite useful in many instances.

The device is simple, can be easily connected, and readily used, and will not interfere 95 with the desired operation of the set or with the operating connections of the set in any way.

I am aware that many changes may be made and numerous details of construction varied throughout a wide range without de- 100

parting from the principles of this invention, and I, therefore, do not purpose limiting the patent granted hereon otherwise than as necessitated by the prior art.

5 I claim as my invention:

- 6 1. A microphone, adapted to be connected to a radio set, including the usual diaphragm and connecting wires, one of said wires adapted to be grounded to the set, and the other 10 adapted for connection with the tube actuating the loud-speaker, and a switch as an integral part of said microphone for cutting off the radio reception and cutting in the microphone.
- 15 2. A microphone and a casing therefor, adapted to be connected to a radio set, including the usual diaphragm and connecting wires, one of said wires adapted to be grounded to the set, and the other adapted for connection with the tube actuating the loud- 20 speaker, and a switch mounted within the casing for cutting off the radio reception and cutting in the microphone.
- 25 3. A microphone, adapted to be connected to a radio set, including the usual diaphragm and connecting wires, one of said wires adapted to be grounded to the set, and the other adapted for connection with the tube actuating the loud-speaker, and a switch for simultaneous- 30 ly cutting off the radio reception and cutting in the microphone, said switch comprising a leaf spring mounted on the frame, a set screw in the frame adapted to make electrical contact with the spring, and a push-button for 35 operating said spring.
- 40 4. A microphone for local broadcasting, including wire connections to a radio set, one of said connections adapted to be applied to the power tube for the loud-speaker, and the other adapted to be grounded to the chassis of the set, and a manually operated switch as an integral part of said microphone for making and breaking said connections.
- 45 5. A microphone, adapted to be connected to a radio set, including the usual diaphragm and connecting wires, one of said wires adapted to be grounded to the set, and the other adapted for connection with the tube actuating the loud-speaker, and an adjustable contact switch as an integral part of said microphone for cutting off the radio reception and cutting in the microphone.

In testimony whereof I affix my signature.
JAMES R. FOUGH.
